UNITED STATES PATENT OFFICE.

LOUIS W. RICE, OF NEW YORK, N. Y.

DEVICE FOR HOLDING PERFORATED GAME COUNTERS.

Application filed January 31, 1924. Serial No. 689,605.

To all whom it may concern:

Be it known that I, LOUIS W. RICE, a citizen of the United States, residing at 325 Fifth Avenue, New York city, in the county 5 of New York and State of New York, have invented new and useful Improvements in a Device for Holding Perforated Game Counters, of which the following is a specification.

10 The invention is a device for holding perforated game counters or the like, and provides a set of nestable players' stands for holding their "money" in separate stacks of different denominations, and also a storage rack nestable with the player's stands for holding all the counters, also in stacks of different denominations.

The set of players' stands is of improved and simple form, more convenient in use for 20 play and for nesting than existing devices of the general character, and comprises, specifically, a set of four stands, each having four posts arranged on the circumference of a circle, sufficiently far apart to receive stacks of counters of the different denominations, and three holes in the same circle between every two of the posts, the stands corresponding in respect to the positions, numbers and sizes of their posts and 25 holes so that any post will pass through any hole in the nesting operation. By virtue of this construction all of the stands can be alike, and their posts, on which the counters are placed, can be of the same character and 30 diameter in the several stands.

The storage rack can be slipped on over any of the posts projecting upward from the nest of players' stands.

35 In the accompanying drawings, forming a part hereof:

Fig. 1 is a side elevation showing the stands nested and the storage rack in place;

Fig. 2 is a top plan view;

Fig. 3 is a cross-sectional view, on a 45 larger scale, taken on the line 3—3 of Fig. 2;

Fig. 4 is a perspective view of one of the stands; and

Fig. 5 is a perspective view of the storage rack.

50 Each of the players' stands 1 has a sheet metal base 2 formed with a rim 3 to rest on the table and a slightly raised top 4. Secured to the top are four posts 5 arranged on the circumference of a circle and properly spaced to receive four stacks of perforated counters *a*. Between every two of the

posts in each stand, and in the same circle therewith, is a series of three holes 6 through the base, making twelve holes in each stand. The posts and the holes are 60 alike in all the stands, and they are so disposed that the four posts of any stand will pass through any set of four holes in any other stand. The four stands can thus be nested in any order. The four posts of the 65 bottom stand then pass through four holes of the stand next above, the remaining holes of this stand being unoccupied, the eight posts of these two stands pass through eight 70 of the holes in the next stand above, and the twelve posts of these three stands occupy 75 all the holes of the stand on top.

The nestable storage rack 7 may be somewhat modified in form, but it is preferably made of two cross-arms 8 united at the middle, and having perforations 9 inwardly of their ends. These holes will slip over any four of the posts of the nest of stands, ninety degrees apart. Outwardly beyond the holes the arms carry four posts 10, 80 which when everything is nested are disposed outside the circle of the posts 5. These four posts will receive the entire collection of counters for the game, it being convenient to place a different denomination 85 on each post.

The invention is not necessarily limited to a set of four players' stands, and if there should be more it will be obvious that there will be more holes in the stands for the 90 posts to pass through in nesting, so that there will be one less hole between every two posts of a stand than there are stands in the set.

95 What is claimed as new is:

1. A set of stands for perforated game counters, each stand comprising a base and a plurality of posts rising therefrom to receive stacks of counters of different denominations, the posts being alike in all the 100 stands of the set, each base being further provided with holes disposed in a circle with the posts, the number of holes between two posts in each stand being at least as numerous as the remaining number of stands in the set, the construction being such that any post will pass through any hole in nesting the stands.

2. The combination with a set of players' stands for perforated game counters, each 110 stand comprising a base plate having posts and holes disposed in a circle for nesting,

of a storage rack adapted to nest with the nest of players' stands.

3. The combination with a set of players' stands for perforated game counters, each stand comprising a base plate having posts and holes disposed in a circle for nesting, of a storage rack adapted to nest with the nest of players' stands and having posts to receive all the counters in the different denominations.

4. The combination with a set of players' stands for perforated game counters, each stand comprising a base plate having posts and holes disposed in a circle for nesting,

of a storage rack adapted to nest with the nest of players' stands and having posts outside the ring of posts of the players' stands.

5. The combination with a set of players' stands for perforated game counters, each stand comprising a base plate having posts and holes disposed in a circle for nesting, of a storage rack comprising cross-arms perforated inwardly of their ends to slip over the posts of the nest of players' racks and carrying posts on their outer portions.

LOUIS W. RICE.
